United States Patent Office

Des. 193,814
Patented Oct. 9, 1962

193,814

UNDERWATER CAMERA

Eugene D. Vezzani, 3147 Saybrook Drive NE.,
Atlanta, Ga.

Filed Nov. 1, 1961, Ser. No. 67,331

Term of patent 14 years

(Cl. D61—1)

FIG. 1

FIG. 2

FIG.3

FIG.4

FIG. 5

FIG. 6

FIGURE 1 is a perspective view of an underwater camera showing my new design.

FIGURE 2 is a top plan view thereof.

FIGURE 3 is a left elevation thereof.

FIGURE 4 is a front elevation thereof.

FIGURE 5 is a right elevation thereof.

FIGURE 6 is a rear elevation thereof.

The two circles on the upright portion as shown in FIGURE 5 represent electrical sockets.

I claim:

The ornamental design for an underwater camera, as shown and described.
